UNITED STATES PATENT OFFICE.

WILLIAM JAMES WALSH, OF HAMILTON, CANADA.

ADJUSTABLE SWIVEL SWING BOOK-HOLDER BRACKET.

SPECIFICATION forming part of Letters Patent No. 669,935, dated March 12, 1901.

Application filed May 21, 1900. Serial No. 17,330. (No model.)

To all whom it may concern:

Be it known that I, WILLIAM JAMES WALSH, a citizen of Canada, residing at Hamilton, in the county of Wentworth, in the Province 5 of Ontario, Canada, have invented new and useful Improvements in Adjustable Swivel Swing Book-Holder Brackets, of which the following is a specification.

My invention consists of a projecting wall-bracket arranged and devised to receive and hold the secured back or bound part of a book, said bracket, with the book, being capable of adjustment to various positions for reading and to a closed position when not in 15 use.

The objects of my invention are, first, to provide a book-holder which shall be of suitable incline for reading; second, to provide a book-holder which shall be capable of swivel and swing adjustment, and, third, to afford facilities for the placing of the same to a parallel position with the wall or other place to which the bracket may be fastened. I attain these objects by the mechanism illustrated in 25 the accompanying drawings, in which—

Figure 1 is a side elevation of the book-bracket with the outline of a book, the back or bound part of the book secured therein. Fig. 2 is a plan of the book-bracket. Fig. 3 30 is a detail plan of the bracket-bearing, and Fig. 4 is a detail front elevation of the swivel part of the bracket.

Similar letters refer to similar parts throughout the several views.

35 In the drawings the bearing part of the bracket is indicated by *a* and has a suitable flange *b* for fastening the same to a wall or other convenient and suitable place.

c represents the book-supporting arms of 40 the bracket of suitable incline for reading and has inner base-flanges *d* for the back of the book *e* to rest on. The wall ends of the arms *c* are brought together and intersect to form a round shank *f* with circular button-headed end *h*, which is adapted to fit easily 45 into the socket *i* of the arm-bearing *j* to retain said arms in position. This bearing *j* has a front opening *k* for the shank *f* of the arms *c*. The said socket *i* and the front opening *k* both open out on the top of the bearing 50 *j* to allow entrance of the shank *f* with its head. In order to allow a swivel side adjust-

ment or movement to the book-supporting arms, as seen in broken lines in Fig. 2 of the drawings, the arm-bearing *j* has a lower round shank *m*, which fits into the round socket *n* of the bracket *a*. This socket allows freedom to the arms *c* to swing the same to a suitable degree for the proper reading of the book. 55

The book *e* is shown slightly in perspective 60 and is secured to the inclined arms *c* by means of suitable bolts *o* or laces through said arms or by other approved method. It will be observed that on account of the circular construction of the head *h* the arms, with the 65 book, may be slightly revolved or inclined to either side to suit the reader and remain in position and also may be turned completely over and allow the leaves of the book to hang downward, this latter keeping the book dust-proof and clean. It will also be noticed that the arms, with the book, may be swung to a parallel position with the wall or wherever the bracket may be attached to. 70

This book-holding device is adapted for 75 catalogues, telephone - index books, music-books, and other books.

It will be noticed that the flanges *d* of the arms *c* terminate a distance from the shank *f* to facilitate the widening apart or the contracting of the arms to suit varying thickness of books and also that the arms, with the book, may be easily removed from the socket *i* for reading or other purposes. This book-holding device is conducive to the preservation 85 of the corners of the leaves of the book.

Various changes in the form, construction, and minor details of this invention may be resorted to without departing from the spirit and scope thereof. Hence 90

What I claim as my invention, and desire to secure by Letters Patent, is—

1. In a book-holder, arms, inner flanges as a base to said arms to support the back of a book, a round shank formed at the inner and intersecting end of said arms, a round head at the end of said shank, a bracket, a bearing having swivel connection with said bracket, and provided with a socket and said round head capable of revolving in the socket in 95 said bracket, as described.

2. In a book-holder of the character described, arms to receive the back of a book, base-flanges between said arms to support the 100

book, means to secure the book between said arms, a round shank formed at the inner and intersecting end of said arms, a round head at the end of said shank, a bracket, a bearing capable of swivel movement in said bracket, and having a socket to admit and hold said shank and head and to allow said arms to revolve, as described.

3. A book-holder, comprising arms, base-flanges on the inner side of the arms to support a book, between the arms and on the

flanges, a round shank formed at the intersecting end of the arms, a round head at the end of the shank a bearing with socket for said head to allow the book-holder to revolve, a lower shank on the bearing, a bracket for said bearing to allow swivel movement to the book-supporting arms, as described.

WILLIAM JAMES WALSH.
